UNITED STATES PATENT OFFICE.

ERNEST W. RUSSELL, OF VALLEJO, CALIFORNIA.

MACHINE FOR MAKING CHANGE.

1,070,920.

Specification of Letters Patent. Patented Aug. 19, 1913.

Application filed May 5, 1911. Serial No. 625,171.

To all whom it may concern:

Be it known that I, ERNEST W. RUSSELL, a citizen of the United States, residing at Vallejo, in the county of Solano and State 5 of California, have invented new and useful Improvements in Machines for Making Change, of which the following is a specification.

In view of the general use of automatic 10 vending machines a necessity has arisen for a mechanism for making change so that a coin of proper value may be obtained by a person desiring to operate a vending machine and not having at hand a coin of pre- 15 scribed value.

The invention provides a mechanism which may be used independently of or in connection with a vending machine, the purpose being to enable a person upon de- 20 positing a coin in the machine to obtain the value thereof in change, thus for instance a silver dollar deposited in the machine will result in a return to the operator of four quarters and a twenty-five cent piece of five 25 cents, and a nickel of five one cent pieces. It is to be understood that the machine may embody similar change making mechanisms one for a silver dollar, one for a half dollar, one for a quarter dollar 30 and one for a five cent piece or nickel, the change making mechanisms being similar but varying in size.

A further purpose of the invention is the provision of a change maker which will 35 operate only in connection with a coin of prescribed value, a coin of less value failing to make proper connection for operation of the mechanism and a coin of greater value not being permitted to enter the coin slot. 40 The mechanism also embodies novel means whereby ample provision is had for release of the operating coin and a discharge of the change, thereby preventing the same coin being used for operating the machine a sec- 45 ond time.

The invention consists of the novel features, details of construction and combination of parts, which hereinafter will be more particularly set forth, illustrated in the accompanying drawings, and pointed out in the appended claims.

Referring to the drawings, forming a part of the specification, Figure 1 is a view in elevation of a change making mechanism embodying the invention, the casing or cabinet being shown in section. Fig. 2 is a view

similar to Fig. 1, the parts being in section. Fig. 3 is a top plan view. Fig. 4 is a horizontal section on the line $x-x$ of Fig. 1. Fig. 5 is a transverse section on the line $y-y$ of Fig. 1. Fig. 6 is a vertical section on the line $w-w$ of Fig. 3. Fig. 7 is a detail view in perspective of the hollow abutment.

Corresponding and like parts are referred 65 to in the following description, and indicated in all the views of the drawings, by the same reference characters.

The change making mechanism illustrated is adapted for delivering five one cent pieces 70 for each five cent piece deposited in the machine. The operating parts are supported upon a plate 1, which may be fitted to the casing or cabinet 2 in any manner or relative position according to the specific 75 application of the change maker. The magazine for receiving the one cent pieces or coins to be delivered in change is indicated at 3 and may be of any length or diameter to meet existing conditions. The magazine 80 3 is elevated or spaced from the plate 1 a distance corresponding to the depth of the pile or number of coins to be delivered in change at each operation of the machine. A tube 4 leads from an opening in the plate 85 1 to an opening in the front of the casing or cabinet 2 and serves to direct the change into a cup 5 arranged upon the front of the casing opposite the delivery end of the tube 4. The receiving end of the tube 4 is 90 out of line with the magazine 3. A coin ejector 6 is pivoted between its ends to the plate 1 and has a pocket at one end arranged to register with the magazine 3 and with the tube 4, the pocket being of a diameter corresponding to the diameter of the coin to be delivered in change and equal in depth to the pile or number of coins to be delivered at each operation. The coin 95 ejector 6 operates over the plate 1 and below the magazine 3 and in one position its pocket registers with the magazine and in another position it registers with the opening in the plate 1 in register with the receiving end of the tube 4 so as to deliver 100 the change into said tube. The magazine 3 has a vertical slot 7 formed in a side to receive an extension 8 projecting laterally from a weight 9, which is supported upon the pile of coins contained in the magazine 110 3. The weight 9 is connected by means of a wire 10 with one pole of a battery 11, the

opposite pole of said battery being connected by means of a wire 12 with a contact 13 arranged to be engaged by the extension 8, which constitutes a movable contact. An 5 alarm 14 is located in the length of the wire 12 so as to give warning when the magazine is nearly or quite empty so that the same may be replenished with change. A chain or flexible connection 15 is connected 10 with the weight 9 and passes over a guide 16 and has a counterweight 17 attached to its opposite end, said counterweight being arranged to operate in a casing 18 mounted upon the plate 1 or in any convenient manner. The purpose of the counterweight 17 is to take up any slack in the chain or connection 15.

A flattened tube 19 extends from a coin slot formed in the front of the casing 2 20 and an opening formed in the plate 1 and constitutes the coinway for directing the coin deposited in the machine to the change operating mechanism. A coin receiver 20 is located at the inner or delivery end of 25 the coinway 19 and is of cylindrical form and closed at opposite ends. The coinway 19 connects with one end of the coin receiver to deliver the coin thereto. The lower portion of the coin receiver is cutaway, 30 forming an opening 21 through which the coin is discharged. A guide 22 is arranged opposite the opening 21 of the coin receiver to give proper direction to the coin in its delivery. A spring actuated plunger 23 is 35 arranged to operate through an opening formed in the front of the casing 2 and through an opening formed in the outer end of the coin receiver 20. The inner end of the plunger 23 clears the outer end of 40 the coin receiver so as not to obstruct the entrance of the coin therein from the coinway 19. After the coin has been received in the part 20 a pressure upon the plunger 23 forces the coin rearward in the receiver 45 20 and operates the change mechanism. A hollow abutment 24 is arranged to operate within the coin receiver 20, its outer diameter corresponding with the diameter of the prescribed coin adapted to operate the mechanism. The lower portion of the hollow 50 abutment is cutaway, as indicated at 25, for the discharge of the coin, said cutaway portion corresponding with the opening 21 in the lower front portion of the coin receiver. A spring actuated stem 26 is connected with the hollow abutment 24 and normally holds the latter projected. The front end of the hollow abutment is spaced from the front end of the coin receiver a distance 55 to receive the operating coin. In the event of the coin deposited in the coinway 19 being of a less diameter than the prescribed coin designed for operating the machine it will pass through the hollow abutment 24 60 upon pressing the plunger 23 inward and

discharge through the openings 25 and 21. However, when a coin of predetermined value is deposited in the coinway 19 and enters the receiver 20 it engages the front end of the hollow abutment 24 upon pressing inward upon the plunger 23 and moves said hollow abutment and the spring actuated stem 26 connected therewith inward and operates the change mechanism. The coin ejector 6 has the end opposite that provided with the pocket arranged to engage the stem 26 so as to move therewith. Rearward movement of the hollow abutment 24 effects a movement of the coin ejector 6 to cause a delivery of the change contained in the pocket thereof into the delivery tube 4. The parts have a prescribed movement and when the plunger 23 has reached the limit of its inward movement the hollow abutment 24 is engaged by means of a dog 27 so that when the plunger 23 moves outward the operating coin is released and drops into a receptacle arranged within the cabinet to receive the same. 70 75 80 85

The dog 27 is pivoted between its ends to the plate 1 and one end operates through an opening formed in a side of the coin receiver 20 and is adapted to engage a shoulder 28 on a side of the hollow abutment to hold the latter at the limit of its inward movement until the dog 27 is stripped by means of the plunger 23 when reaching the limit of its outward movement. A link 29 connects the dog 27 with one end of a lever 30, the opposite end of said lever being connected to a plate 31 in which is formed a longitudinal slot 32 in which is arranged to operate a pin 33 carried by the plunger 23. A spring 34 normally exerts a pressure upon the dog 27 to throw its inner end in engagement with the shoulder 28 the instant said shoulder clears the dog. As the plunger 23 reaches the limit of its outward movement the pin 33 engages the outer end of the slot 32 and moves the plate 31 outward and trips the dog 27 and releases the hollow abutment 24, which springs forward by the action of the spring arranged to coöperate with the stem 26. 90 95 100 105 110

The receptacle 35 arranged within the cabinet has its front flush with the front of the cabinet and covered by a piece of plate glass so as to expose a number of coins. The bottom of the receptacle 35 is movable and counter-balanced so as to support a number 115 of coins in position for observation and when the weight of a given number of coins overcomes the counterbalance of the bottom 36 said bottom swings downward and delivers the coins into the receptacle. The bottom 36 120 is pivoted and is normally retained in position by means of a weight 37. By retaining a number of the coins in view a person is deterred from making an attempt to operate the machine by means of a slug or dummy. 125 130

The change mechanism may be located in any convenient position and any number of mechanisms may be provided according to the coins for which change is to be given.

5 To operate the machine a coin 38 of prescribed value is introduced into the coinway 19 and is directed thereby into the coin receiver 20 between the inner end of the plunger 23 and the front end of the hollow abutments 24. Inward pressure upon the plunger 23 causes rearward movement of the hollow abutment 24 and its spring actuated stem 26, thereby operating the coin ejector 6, whereby the coins representing the change 15 are withdrawn from the lower end of the magazine 3 and delivered into the tube 4 and directed by said tube into the cup 5. When the plunger 23 reaches the limit of its inward movement the dog 27 engages the hollow abutment 24 and prevents the same following the plunger 23 and as a result the coin 38 is released and drops through the openings of the coin receiver and hollow abutment into the receptacle 35. As the 20 plunger 23 reaches the limit of its outward movement the plate 31 is tripped and releases the hollow abutment which springs outward and at the same time returns the coin ejector into position to receive the number of coins representing the change to be delivered at the next operation of the machine upon depositing a coin 38 into the coinway 19 and pressing inward upon the plunger 23.

From the foregoing description, taken in 15 connection with the accompanying drawings, the advantages of the construction and of the method of operation will be readily apparent to those skilled in the art to which the invention appertains, and while I have

described the principle of operation of the invention, together with the device which I now consider to be the embodiment thereof, I desire to have it understood that the device shown is merely illustrative and that such changes may be made when desired as 45 are within the scope of the claims appended hereto.

Having thus described the invention what is claimed as new, is:—

In coin operated mechanism, the combination of a coin receiver having a discharge opening in its lower portion at a point between its ends, a hollow abutment slidably mounted within the coin receiver, means normally pressing the abutment forwardly, 50 a manually operable member arranged to enter the coin receiver, a coinway arranged to deliver a coin into the coin receiver between the manually operable member and the abutment, a projection at one side of the 55 hollow abutment, a dog arranged to travel upon said projection and to engage an end thereof to hold the abutment in retracted position, a member having a limited movement with reference to the manually operable member, and connecting means between the said 60 dog and the last mentioned member to admit of the said dog being tripped when the manually operable member is near the limit of its return stroke to effect release of the 65 abutment.

In testimony whereof I affix my signature in presence of two witnesses.

ERNEST W. RUSSELL.
